UNITED STATES PATENT OFFICE

JOHAN ANTON NILSSON, OF MALMO, SWEDEN, ASSIGNOR TO SVENSKA BINDGARNSS-FABRIKENS AKTIEBOLAG, OF MALMO, SWEDEN, A CORPORATION OF SWEDEN

TWINE-HOLDER FOR SELF-BINDING HARVESTERS

Application filed September 29, 1930, Serial No. 485,260, and in Sweden October 11, 1929.

My invention refers to a multiple twine-can or holder for the twine used for the automatic binding of the sheaves in self-binding harvesters, the type of the harvesting machine itself and the binding apparatus used in connection therewith being independent of the invention.

In the types of twine-holders hitherto in use for the aforesaid purpose, two balls of twine have been placed one upon the other in a common can, the delivery of the twine commencing from the interior of the uppermost ball. The outer end of the upper ball has been connected with the inner end of the lower one, and after the upper ball has been consumed, the delivery takes place from the lower one in the same manner. Finally, when there remains a thin shell of the lower ball only, the can must be refilled, and this is performed by lifting the highly reduced lower ball out of the can, connecting the outer end thereof with the inner end of a fresh ball and placing the latter on the bottom of the can, the partly used ball being again inserted on top of the fresh ball.

It is evident that this handling of a ball, which is substantially consumed, is very delicate, and frequently it results in that the said shell of a ball is pressed flat and otherwise deformed so that the twine gets entangled and is either delivered in the form of an entangled knot or torn off, and mostly this mishap escapes the notice of the attendant of the harvester until a plurality of unbound sheaves have been fed out from the same. Besides, in twine-cans of this kind, it is not possible to use balls which completely fill the can in transverse direction, but the balls must be a little smaller than the latter. Then, they will get no steady seat in the can, and when being thrown about therein during the travel of the machine on a frequently very uneven ground they are still further liable to be deformed and to form entangled knots.

According to the invention, all of these inconveniences are eliminated, and generally the invention is based on the principle of using a plurality of separate cans each

adapted for holding one single ball, whereby the inner end of one ball is connected with the outer end of another one. Based on this general principle, the construction of the can may naturally vary in many ways in 55 practice. Although for all practical purposes it may be found sufficient to employ two separate ball cans only, the apparatus may naturally be provided with a greater number thereof, in case the space available 60 in the harvester is sufficient therefore. In several instances it may be favorable to employ more than two cans, as it is evident that the greater quantity of twine that can be carried by the machine at the same time, 65 the less frequently it must be stopped for refilling the cans. Further, it is suitable to place all of the cans substantially at the same level in the machine, i. e. side by side, but nothing prevents another positioning of the 70 same, for instance in a pile above each other, the main point being that separate cans are used for each ball, so that no lifting out of partially consumed balls is required for the refilling. Hereby it will also be possible 75 to use so large balls that they completely fill out, and even fit tightly within, the cans, and each ball will thereby be given a steady seat in its can. Furthermore the steady seat may also be secured by means of small pins 80 adapted to stick into the bottom end of the balls, such pins being mainly adapted to prevent a rotation of the balls during the delivery of the twine.

Hence, when practicing the invention, the 85 ball in one can is at first entirely consumed, and by the connection of the different balls the consumption of another ball is thereafter automatically commenced. When the last ball has been substantially consumed, the apparatus must be refilled, and this step is effected simply by insertion of fresh balls in the empty can or cans, whereafter the ends of the balls are connected as stated above and the inner end of the first of them with the 90 outer end of the remaining ball rest, the said outer end of which has previously been positioned in readiness for such purpose.

The guiding of the twine outside of the cans may also be effected in different ways, 95

and the means used heretofore will mainly be dependent for their construction of the number of cans employed. A pair of parallel bars spring actuated in a direction towards each other and serving also as a tensioning means for the twine and extending along the delivery opening of all of the cans may, however, be considered as a suitable embodiment of the aforesaid guiding means.

10 The invention is illustrated in the accompanying drawing, which refers to an embodiment of invention comprising two twine-cans placed side by side. In the drawing:— Fig. 1 shows an elevation of the twine holder partly in section, and

15 Fig. 2 shows a plan view of the same. In the drawing, the references 1 and 2 represent the two cans which are carried by a common base member 3 and completely filled 20 with the twine balls 4 and 5 respectively, which preferably consist of so called "cheese spools". The volume of the cans shall be the greatest possible in order that the apparatus shall have the greatest possible holding 25 capacity.

In the embodiment shown, the cans are open in upward direction and closed by removable lids 6 and 7 respectively, such lids at their inter-facing sides being provided 30 with radial slots 8 and 9 respectively extending substantially from the centre and entirely to the very edge of each lid. The lids 6 and 7 are mounted on hinges 10 and 11 and at the edges of the lids facing the hinges, the 35 lids are interconnected by means of a rod 12 carrying a guide eye 13 for the twine positioned between the cans. The locking of the lids in a closed position can naturally be performed in many different ways, but according 40 to the embodiment shown the locking means consist of a rod 14 connecting the lids at the edges opposite to the hinges, such rod 14 being provided with a slot for coaction with a screw 15 hingedly connected with the base member 3 and provided with a winged nut or the like.

45 Approximately at their centres the lids are also interconnected by means of a bar 16 positioned parallel to the slots 8, 9, and another bar 17 is loosely placed upon the former. At its ends the bar 17 is provided with free holes for screws 20, 21 extending from the lids and provided with wing nuts 18, 19, a coil spring 22 and 23 respectively being positioned around each of the said screws between the nuts thereon and the ends of the upper bar 17, so that the bars 16 and 17 are pressed towards each other with a force corresponding to the tightening of the wing nuts 20, 21, such force or pressure being apparently variable at will.

50 As will be seen from the drawing, the flat bars 16 and 17 are not truly parallel, but seen in transverse direction they form a small angle with each other the gap of such angle

being directed towards the side from which the twine is to be entered between them.

At that side, at which the twine leaving the tensioning bars shall go through the guide eye 13, the edges of the bars ought to be rounded off so as not to have any tearing or scraping action on the twine, and the angular inter-relation of the bars referred to above is intended for facilitating the entrance of eventual knots on the twine between them.

One of the cans, for instance the can 5, is exteriorly provided with a spring clip or the like 24 adapted for affixing one end of the twine, and interiorly the bottoms of the cans may be provided with upstanding pins or spikes (not shown) extending into the balls from beneath and preventing their rotation within the cans.

When the twine-holder is to be used, a ball of twine is inserted in each of the cans such balls being of a size sufficient for completely filling up the cans. The outer end of one ball, for instance in the can 1, is drawn out through the slot in the lid on the same and affixed to the clip 24, the inner end of the same ball by means of a knot being connected with the outer end of the ball in the other cup 2, the latter twine-end being drawn out through the slot in the lid on the last mentioned can. Finally the inner end of the ball in the can 2 is carried between the tensioning bars 16, 17 and out through the guide eye 13 to the binding apparatus of the harvester. In this case, when the twine in the first ball, i. e. the ball 5, has been totally consumed and the twine in the second ball 6 had also been substantially consumed, the lid 7 is opened, and a fresh ball is inserted in the can 2. The twine end affixed to the clip 24 is released and connected with the inner end of the said fresh ball, the outer end of which in its turn being affixed to the clip 24 for use when inserting a fresh ball in the second can 1.

Herefrom it will be apparent that the delivery of the twine will always take place from the interior of the balls, and when once inserted, it is not needed to handle any more or less consumed ball, but the balls may be left entirely to themselves after insertion and until they are completely consumed. Hence, the balls may be made to fit very closely into the cans, and the risk for deformation of more or less consumed balls by changing their position when refilling the holder is entirely eliminated. The tensioning of the twine leaving the guide eye 13 may naturally be varied by more or less tightening of the wing nuts 18, 19. The complete arrangement may easily be mounted and demounted on any self-binding harvester now in use.

Having now described my invention and the manner in which it is to be performed I declare that what I claim is:—

1. In a twine-holder for self-binding harvesters, two separate twin-cans each adapted

for the accommodation of one single twine ball, a lid on each can, a slot in each lid extending substantially from the center portion and entirely to the edge thereof, the 5 open ends of the slots being positioned so as to face each other, and a twine tensioning and guiding means common to both cans and mounted closely adjacent to said slots so as to be passed by the twine fed out through 10 the same.

2. A twine-holder for self-binding harvesters according to claim 1, in which the cans are mounted substantially at the same level, and being of substantially the same 15 height, and provided with lids interconnected by means of the twine tensioning and guiding means mounted on the lids.

3. In a twine-holder for self-binding harvesters, two separate twine-cans each adapted 20 for accommodation of one single twine ball, a lid on each can, a slot in each lid extending substantially from the center portion and entirely to the edge thereof, the open ends 25 of the slots being positioned so as to face each other, a first bar member positioned along the slots in the lids, a second bar member loosely laid upon the former and shaped to form a small angle with the latter in transverse 30 direction, spring means acting upon the bar members to press them together, and guide means for guiding the relative movement of the bar members in relation to each other.

4. A twine-holder for self-binding harvesters according to claim 3, in which the first 35 bar member is rigidly connected with the lids to interconnect the same, the guide means at the ends of the bar members consisting of screws extending from the lids and provided with nut means, and coil springs surrounding 40 the said screws and interposed between said nut means and the second bar member.

In testimony whereof I have signed my name to this specification.

JOHAN ANTON NILSSON.
